CONTROL ARM FOR A TREMOLO UNIT FOR A GUITAR

James Ormston Burns, Buckhurst Hill, Essex, England,
assignor to Ormston Burns Limited, London, England,
a British company

Filed Dec. 12, 1962, Ser. No. 72,821

Claims priority, application Great Britain July 28, 1962

Term of patent 14 years

(Cl. D56—1)

FIG. 1.

FIG. 2.

FIG. 1 is a front view of a control arm for a tremolo unit for a guitar embodying my new design, and

FIG. 2 is a right side elevational view.

I claim:

The ornamental design for a control arm for a tremolo unit for a guitar, substantially as shown.
